US0D1024508S

(12) United States Design Patent (10) Patent No.: US D1,024,508 S
(45) Date of Patent: * Apr. 30, 2024

(54) SHOE

(71) Applicant: SHENZHEN STARLINK
NETWORK TECHNOLOGY CO.,
LTD, Shenzhen (CN)

(72) Inventor: Jie Huang, Singapore (SG)

() Term: 15 Years

(21) Appl. No.: 29/880,893

(22) Filed: Jul. 28, 2023

Related U.S. Application Data

(63) Continuation-in-part of application No. 29/772,940, filed on Mar. 5, 2021, now Pat. No. Des. 996,788.

(51) LOC (14) Cl. 02-04

(52) U.S. Cl.

USPC D2/971; D2/925

(57) CLAIM

The ornamental design for a shoe, as shown and described.

DESCRIPTION

FIG. 1 is a perspective view of a shoe showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the shoe that form no part of the claimed design.

1 Claim, 8 Drawing Sheets
